BALLOON AND METHOD OF MAKING

William F. Huch, St. Paul, and Raymond I. Hakomaki, Minneapolis, Minn., assignors to General Mills, Inc., a corporation of Delaware

Application June 25, 1951, Serial No. 233,282

15 Claims. (Cl. 244—31)

1

This invention relates to improvements in balloons and more particularly to small balloons and their method of manufacture.

In various sciences, such as meteorology, balloons are sent aloft, often to extremely high altitudes to determine various phenomena of the atmosphere. Balloons are frequently sent aloft to determine movements of air currents and their speed and direction of movement. These balloons may be sent to various altitudes as the air currents vary in direction and speed at different altitudes. Balloons are often sent aloft in large numbers, and from the dispersion pattern formed when they land, the flight of the average balloon and the effects of dispersion by the air currents may be determined. Because of the long periods of time aloft, the difficulty of procuring the balloons after they have landed, and the need for large numbers of balloons, there is a great demand for an economical dispensable balloon which is so low in cost of manufacture that it may be flown only once.

Since the balloons are often flown only to track the course of wind, it is unnecessary that they be of large size. In fact, it is desirable that they be small in order to be most economical from a standpoint of saving material. The size is partially determined by the amount of gas necessary to lift the weight of material to the desired height and, therefore, the use of very lightweight material is desirable as it permits the construction of a small balloon. These balloons, which are sent into the stratosphere, may remain aloft for days and be subjected to all kinds of weather, rain, buffeting by air turbulence, extreme cold of high altitudes, ozone, and the rays of the sun. It becomes necessary, therefore, to provide a balloon of material which is able to withstand these adverse elements.

When the balloon is released on the ground and rises to high altitudes, the atmospheric pressure decreases, causing the gas to expand. If the balloon is vented to allow escape of gas to compensate for the expansion, the gas which is lost no longer contributes lifting qualities. Further, with the heavy buffeting by wind which a small balloon receives and with the difficulty of keeping a small unweighted balloon in an upright position it is difficult to provide a suitable venting device and a venting or valving device adds to the cost of the balloon.

There is also a demand for a small light-weight balloon which is capable of carrying a load and which can be inexpensively made by mass production methods. A use for this type of balloon is also found in the studies of air currents.

2

A simple way to check the path of flights of weather balloons is to send each one aloft with a message which directs the finder to return information of the place and time of landing of the balloon. When this information is returned by the balloon finder on a large number of balloons, the wind currents and the dispersion pattern are ascertained.

It is usually necessary that the message or object carried by the balloon be protected against the elements which will normally attack it in all-weather flights. High altitudes require a very durable balloon and normally require a durable container for the payload.

15 A balloon meeting the above qualifications will find demand in a great many other fields. In national defense, for example, there is a demand for inexpensive balloons which can be cheaply made in large numbers for use as targets or for carrying pay loads in the form of messages, incendiaries, objects which give misleading radar pictures and various other objects.

10 An inexpensive balloon capable of carrying a protected message and being flown with a known dispersion pattern on prevailing winds could be very useful for effective transmittal of propaganda to the enemy, both civilian and military. The same principles might be used commercially for the dispersion of advertising matter.

15 An object of the invention is to provide a small balloon which may be sent aloft in great numbers, which is imperishable in all adverse weather conditions and which is suitable for high altitude weather flights.

20 Another object is to make small balloons of economical and light-weight material by a method which is rapid and simple, thereby reducing the cost of manufacture, and which is suitable for mass production of balloons or for the production of single balloons as the demand arises.

25 Another object is to provide a small balloon suitable for high altitude atmospheric flights and which obviates the necessity of providing a pressure release means to compensate for the expansion of the lifting gases contained within the balloon.

30 A further object of the invention is to provide a load-carrying balloon which will not be damaged by the air turbulence, by moisture, heat, cold or other atmospheric conditions and which will also protect its pay load from these adverse atmospheric conditions.

35 Another object of the invention is to provide a balloon suitable for carrying a pay load which

3
will completely obviate the necessity of providing protective containers for carrying the load and also eliminate the need for supporting lines for attaching the containers to the inflated balloon envelope.

Other objects and advantages will become apparent from the following specification taken in connection with the accompanying drawings, in which:

Fig. 1 is a perspective view of a length of 10 tubular-shaped material from which the balloon envelopes are made;

Fig. 2 is a side elevation showing the balloon envelope sealing mechanism in section;

Fig. 3 is a plan view showing the sealed balloon envelope;

Fig. 4 is a plan view showing a message as an example of an object which the balloon is suitable for carrying;

Fig. 5 is a sectional view of the balloon taken 20 along line 5—5 of Fig. 3;

Fig. 6 is a sectional view of the balloon taken along line 6—6 of Fig. 3;

Fig. 7 is a plan view illustrating the manner of forming the opening in the balloon for inserting the object;

Fig. 8 is a perspective view of a balloon showing the opening formed in Fig. 7;

Fig. 9 is a plan view illustrating the manner of sealing the opening;

Fig. 10 is a plan view of the balloon showing the manner of forming the inflation opening;

Fig. 11 is a perspective view illustrating the inflation of the balloon;

Fig. 12 is an enlarged sectional view taken 33 along line 12—12 of Fig. 10;

Fig. 13 is a perspective view showing the sealing of the inflation opening;

Fig. 14 is a front elevation illustrating a heating device for sealing the balloon opening;

Fig. 15 is a perspective view of a completed balloon;

Fig. 16 is a plan view of the corner of the balloon illustrating the manner of opening the balloon for inflation;

Fig. 17 is a perspective view of the corner of the balloon illustrating the opening formed;

Fig. 18 is a perspective view illustrating the inflation of the balloon;

Fig. 19 is an enlarged plan view of the corner of the balloon illustrating the sealing of the inflation opening; and

Fig. 20 is a perspective view showing the condition of a balloon at a high altitude with the lifting gas expanded.

Referring to Fig. 1, a length of tubular balloon material 24 is illustrated. This material may be of any suitable type but a thermoplastic is preferred, such as polyethylene which is a non-extensible material and, for convenience, the specification will refer to the balloon material as polyethylene or thermoplastic. Although polyethylene and other thermoplastics may be capable of being stretched slightly with the application of forces, they may be regarded as being non-extensible as contrasted to material such as rubber. Polyethylene film, suitable for the purposes desired, is extremely light in weight and can withstand extreme cold, such as is encountered in high altitude flights, without becoming brittle or without cracking. It also is not damaged by the heat of the sun rays and moisture has no effect on it. The tubular balloon material is shown in section in Fig. 5. The polyethylene stock shown is supplied on rolls 26 (Fig.

2). The flattened tubular material is fed from the roll over a table 28 which has a channel 30 in the upper surface extending crosswise of the length of the balloon material.

The edges of the end of the material are first brought together and sealed by a bead 32 formed at the end. This may be done by the apparatus shown or by any suitable well known heat sealing devices. The balloon material is then clamped flat on the table a distance back from the sealed bead 32, the distance being equal to the length of the balloon which is desired. The clamping bars 34 press the material flat against the upper surface of the table 28 on each side of the channel 30. A heated sealing and severing member, such as a heated wire 36, is then brought down against the flattened thermoplastic to pass therethrough, severing an end from the length of thermoplastic stock and simultaneously sealing together the severed edges of the opposed layers of the envelope cut from the end of the stock. This severing, of course, also seals the severed edges of the opposed layers of the material coming from the roll, thus forming a bead which will be the forward end of the next succeeding balloon envelope.

The balloon envelope 38 which has been formed (Fig. 3) is now completely sealed, having the side edges 40 and 42 closed by virtue of the fact that the material was originally tubular in form and having the end edges sealed or welded with the sealing beads 32 and 44. This balloon envelope is flat and contains no air and can be stacked or folded for storage and for future use. Fig. 6 shows a sectional view taken from the side of the balloon, showing the construction of the sealing beads at the ends. These beads, if correctly formed, will seal the material with a strength equal to that of the material itself and, being small, add no appreciable useless weight to the balloon. Further no material extends beyond the bead or seam and all available sheet material is utilized in the actual balloon wall. The sectional views in Figs. 5 and 6 show the edges of the balloon as being rounded for purposes of illustration, while actually the balloon envelope is flat as shown in Figs. 2 and 3 since it is completely devoid of all air or gas.

It is to be understood that the balloon envelopes could be formed of various other suitable materials. A thermoplastic material is to be desired, however, primarily because with the method of forming taught by the present invention, three operations may be formed by one step, namely, the severing of a balloon from the length of stock of material, and the sealing of the trailing end of the severed balloon and the sealing of the leading end of the succeeding balloon. These steps are accomplished in one operation by merely bringing the heated sealing wire 36 in contact with the material. With the use of other materials the sealing of the balloon ends and the severing will likely have to be performed in two or more operations and the sealing of the balloon ends may have to be accomplished by the application of a bonding adhesive.

These balloon envelopes are preferably small in size so as to be economical and, since the material is light in weight, a small-sized balloon is capable of ascending to high altitudes. If used to carry loads or payloads as they are often referred to in the balloon art, the load is small and light in weight, such as a paper 46 containing a message, illustrated in Fig. 4. This

balloon load shown as a sheet of paper having printing 48 thereon, may be instead a sheet of light-weight metallic foil, or a light-weight scientific instrument or other similar object, depending upon the use to which the balloon is to be adapted. It will become apparent that the balloon structure taught by the present invention is capable of carrying a variety of loads but, for purposes of illustration, the description will show and refer to the load as a paper containing a message.

If the object to be carried aloft is a message, it will most likely be of paper which must be protected if it is to be flown, launched and permitted to weather in all types of atmospheric conditions. To obviate the necessity of providing a special sealed carrier for the message and to eliminate the provision of special means to attach the carrier to the balloon, the present invention places the message within the balloon and seals the balloon completely against atmosphere. The balloon, being of a light-weight material, can in practical usage be only partially filled with a lighter-than-air lifting gas, and the unfilled space of the balloon will permit expansion of the gases as the balloon ascends to high altitudes where the atmospheric pressure becomes less. Thus, by the elimination of useless weight normally present in load carrier supporting lines, etc., a larger amount of balloon material can be lifted with the same amount of gas. With a larger balloon, no opening need be left in the balloon for relief of expanding gases, as the balloon can be only partially inflated or partially distended on the ground and the additional balloon volume will allow for expansion of the gas. With the balloon envelope completely sealed the escape of gas is prevented when the balloon ascends to lower pressures and the gas expands and distends the balloon. With the balloon completely sealed the object within the balloon is completely protected. The advantage of this structure becomes apparent where a load must be sent aloft which cannot come in contact with the air or cannot be subjected to the moisture or gases which the atmosphere contains. The elimination of supporting lines and load carrier will also permit the use of a smaller balloon. The advantages of saving in cost in simplicity of structure are obvious.

To insert a message into the balloon, a thin sliver 50 is cut from the edge of the balloon, as illustrated in Fig. 7. This may be easily done by cutting off a length of the narrow seam from the balloon end. The length which is cut off is chosen according to the width of the message which is to be inserted. The opening 52, through which the message is inserted into the balloon, is shown in Fig. 8.

After the message is inserted, as illustrated in Fig. 9, a clamping bar 54 is laid along the edge of the flattened material and the opening formed in the balloon. If the material is of thermoplastic, sealing can be easily accomplished by applying a heated sealing iron to the severed edge, whereby the adjoining edges are fused together to form a bead 51. The resulting product is now a completely sealed balloon envelope, having the message inside. If the balloon load is an object such as a tarnishable metal or moisture damageable material which must be protected against the atmosphere, it is protected by the sealed envelope and may be stored in this manner for an indefinite length of time.

The instrument for sealing thermoplastic

seams, may be of any suitable type which is capable of applying heat thereto. A manual sealer is shown in Fig. 14 having a heated sealing wire 56, supported between the ends of the supporting bow 58, which is manually carried by a handle 60. Electrical leads 62 supply heating current to the sealing wire.

When the need arises for sending the balloon aloft with the message enclosed therein, an inflating opening is first placed in the balloon. This may be accomplished, as shown in Fig. 10, by severing a corner 64 from the balloon to form the opening 66. Into this small opening is inserted an inflating tube 68, Fig. 11, supplied with a lighter-than-air lifting gas from a container 70 through a flexible tubing 72. A metering gauge 74 controls the amount of gas inflated into the balloon. The message lies within the balloon as is illustrated in Fig. 12.

The balloon is filled with a sufficient amount of gas to lift the balloon and payload but with insufficient gas to fully distend the balloon as is clearly shown in Figs. 11, 13 and 15. The gas will expand to fill out or distend the balloon as it ascends and the atmospheric air pressure decreases.

The altitude at which the balloon will reach stability and discontinue its ascent which is also called the floating altitude is controlled by the amount of gas placed within the balloon or the volume of the balloon at maximum size. If sufficient gas is placed within the balloon to fully expand it at its maximum altitude, then the flying altitude will be determined by its expanded size. Because of economy of use of materials, the balloons are usually filled with sufficient gas to expand to full size to obtain maximum altitude. Because its maximum size is clearly defined, the present invention is preferably used with a balloon formed of a non-extensible material. With a knowledge of the prevailing winds and the dispersion pattern at a given altitude, the dispersion of the balloons can be readily predicted by filling the balloon with the proper amount of gas to send it to the desired altitude.

When the balloon is sufficiently filled to give it the desired free lift but not to be completely distended, the opening is clamped by clamping member 16 and the edges of the opening are sealed together in an appropriate manner such as by a suitable adhesive. Again, if the balloon material chosen is thermoplastic, the edges may be easily sealed by bringing the manual sealing member, shown in Fig. 14, against the opposed edges. The clamping of the balloon is not absolutely necessary for holding the gas in the balloon as, since the lifting gas is lighter-than-air, it will remain at the upper end of the balloon and, with the balloon in an upright position, the gas will not escape to atmosphere. To absolutely prevent escape of gas in the inflating operation the balloon material may be squeezed tightly around the inflating tube.

It will be recognized that with a very small load the message could be inserted through the inflating hole. The balloon envelope could then be inflated and sealed in the described manner. Also the step of inflating could be done first and the message inserted after inflation. For reasons including the convenience of storage and the protection which the load receives during storage, it is preferred to make the balloon in the manner shown in the drawings.

The completed balloon 78 as is shown in Fig. 15 is manually restrained by a hand 80. When the

7
balloon is released it will carry the message sealed within it aloft, completely protected from the atmosphere and will ascend to the height which is determined by the balloon volume and gross weight carried. The balloon, being sealed will not descend until a portion of the gas has leaked out by natural diffusion. Other means could be provided to determine the length of time aloft, such as placing plugs in the balloon wall which would be broken by the action of the weather elements or by delayed chemical action.

The size of the balloon envelope should be chosen according to the weight carried and the height to which it is to ascend. When the weight of the load is known, a balloon envelope size is chosen which will have sufficient free lift to carry the balloon aloft and which will reach equilibrium at the desired flying altitude.

Figs. 16 through 20 illustrate the manufacture of a balloon for use without a load. A balloon envelope 81 is manufactured by the same steps, as shown in Figs. 1 through 3. Briefly reviewing the steps of formation of the balloon envelope, the tubular material 24 is first sealed across the end with the bead 32. A length of material is then drawn from the roll and the material flattened and clamped a distance back from the sealed bead by the bars 34. A heated severing and sealing wire 36 is then brought down through the material to sever the end from the tubular material and to form a bead weld on the trailing edge of the section severed from the tubular stock to complete the balloon envelope.

When the sealed envelope 81, as shown in Fig. 16, is ready for flight, a small section of the corner 82 is severed from the envelope as forming an opening 84, as shown in Fig. 17. The corner may be removed by any suitable severing means such as a knife or scissors. It will be recognized that this opening could be formed by other means such as by cutting a slit in the wall of the balloon. The easy expedient of removing the corner is preferred because it is extremely simple to reseal this type of opening. This opening provides a port for the entrance of the lifting gas which may be filled in the balloon by inserting the inflating tube 68 into the opening (Fig. 18). The balloon is preferably held in an upright position so that the lighter-than-air gas will move to the top of the balloon and not escape from the opening around the inflation tube. The balloon may also be manually pinched tight around the inflation tube to prevent any gas from escaping. Since the balloon envelope, before inflation, has been absolutely flat, there is no need for provision of a space for air to escape and the gas is merely inflating the balloon, not displacing air.

After the balloon envelope has been partially inflated or partially distended as shown in Fig. 18, the inflation tube is withdrawn and a clamp 86 is placed across the corner of the balloon envelope in the manner shown in Fig. 19. This holds the balloon material in a fixed position and prevents gas from escaping. The edges of the balloon opening are then joined to completely seal the balloon envelope. If the material is thermoplastic, the edges of the opening may be joined by bringing a heated sealing member against them such as is shown in Fig. 14, causing them to fuse and form a bead 88.

The balloon is then ready for ascent. The balloon has the same general shape and configuration as shown in Fig. 15 except that there is

no load inside. The balloons may be released either singly or in groups for purposes of determining air currents, etc., as previously discussed. As the balloon ascends, the decrease of atmospheric pressure causes the gas within the balloon to expand and begin to further distend and fill out the shape of the balloon. When the balloon rises to its floating altitude, where the lift due to the gas and the weight of the balloon material and load reach equilibrium, the balloon will have filled out to its full shape. This fully inflated balloon is shown in Fig. 20. If the balloon is formed of polyethylene, the balloon may be filled with an amount of gas so that it can expand to be full but not burst when at its maximum height. Thus, expansion of the gas will expand the balloon to its maximum design size and within this limit the balloon will not burst.

Thus it will be seen that we have provided an economical balloon suitable for being sent aloft to high altitudes, singly or in large numbers, and which is also suitable for carrying objects aloft. The method of constructing this balloon and preparing it for flying permits the balloon envelopes to be made in large quantities and stored until such time as they are needed. If objects or messages are to be carried they may be hermetically sealed within the balloon and stored for an indefinite time out of contact with the air. The method of making the balloon is rapid and simple and well adapted to mass production of balloons, or to making them singly as the need arises.

We have, in the drawings and specification, presented a detailed disclosure of the preferred embodiments of our invention, but it is to be understood that as the invention is susceptible of modifications, structural changes and various applications of use within the spirit and scope of the invention, we do not intend to limit the invention to the specific form disclosed but intend to cover all modifications, changes and alternative constructions and methods falling within the scope of the principles taught by our invention.

We claim as our invention:

1. The method of making a load-carrying balloon which comprises cross sealing the opposing layers of an end of a tubular section of balloon material, cross sealing the other end of the section of balloon material to form a sealed balloon envelope, cutting an opening in the envelope large enough to accommodate the insertion of a load therethrough, sealing said opening, cutting an inflation opening for inflating the balloon through the opening, and sealing the opening to form a completely sealed envelope.

2. The method of making a load-carrying balloon which comprises cross sealing two ends of a section of tubular balloon material to form a sealed balloon envelope, cutting a strip from the end of the balloon of a length greater than the minimum width of the object to be inserted therein, inserting said object through the opening formed by the cutting operation, joining the severed edges of the opposite layers of material formed by cutting said strip to reseal the balloon, cutting another strip from the end of the balloon to form an opening large enough for the entrance of a lifting gas, and partially inflating the balloon with the lifting gas through said inflation opening, resealing the inflation opening by joining the severed edges which were formed by cutting the strip to form the inflation opening.

3. A method of making a load-carrying balloon

which comprises joining and fusing the edges of the opposed layers at the end of a length of thermoplastic tubular material to form a sealing bead, pressing together the opposed layers of the length of tubular thermoplastic material at a point intermediate the ends of said length, passing a heated sealing member through the material to sever the material and join the severed edges with a sealing bead, the length of the material between said beads forming a sealed balloon envelope, cutting a length of a bead from one end of the envelope of sufficient length to form an opening for insertion of an object, joining the edges of the opposed layers of material formed by said cutting by application of a heated member, cutting a portion from the end of the balloon envelope sufficiently large to permit insertion of an inflating tube, inserting the inflating tube and partially inflating the balloon with a lifting gas, and resealing the balloon by joining the edges of the opposed layers formed by cutting the inflation opening.

4. The method of making a small balloon which comprises cross sealing the ends of a section of tubular material to form a sealed balloon envelope, cutting an opening in said envelope, inflating the balloon with a lifting gas through said opening, and closing the opening to completely seal the balloon with the lifting gas inside.

5. The method of making a small balloon which comprises cross sealing the end of a length of thermoplastic material, simultaneously severing and cross sealing the length of material at a point spaced from said sealed end, cutting a section from the end of the balloon to form an opening, placing a lifting gas in the balloon through the opening, and sealing the interior of the balloon against atmosphere by closing said opening to form a sealed balloon.

6. The method of forming a balloon envelope which comprises forming a lateral seal across the end of a length of tubular material, by bringing the edges together and joining them in an edge-to-edge weld and transversely cutting the tubular material at a point spaced from said end while simultaneously joining together the severed edges of the end of material severed from said length in an edge-to-edge weld to form a sealed balloon envelope.

7. The method of forming a load-carrying balloon for sustained flights of sufficient size to support a payload and formed of a non-extensible material to limit the floating altitude, the method comprising forming a first transverse seal across a length of tubular material joining the layers and cutting transversely across the material at the seal, and forming a second seal across the tubular material separated from the first by the desired balloon dimension and cutting transversely across the material at the seal to form a sealed balloon envelope.

8. The method of forming a load-carrying balloon for sustained flights of sufficient size to support a payload and formed of a non-extensible material to limit the floating altitude, the method comprising cutting a length the desired length of a balloon from the end of a supply of tubular material the end of which is closed, seaming the edges of the cut length to form a balloon envelope, also seaming the edges of the newly cut end of the material supply, severing another length the desired length of a balloon from the new end of the material supply, seaming the cut edges of the severed length to form a balloon envelope, and seaming the edges of the new supply

end to form the closed end for a succeeding balloon, and repeating the above steps throughout the length of material supply to form a plurality of balloons.

9. A balloon which comprises a balloon envelope of a non-extensible material and of a size adapted to lift the load when filled with a quantity of lifting gas not sufficient to completely distend the balloon, the envelope being initially completely sealed in a deflated condition with the balloon interior devoid of all gas, the envelope adapted to being cut open for partial inflation with a lifting gas and to be again completely sealed for launching.

15. 10. A load-carrying balloon comprising a balloon envelope of light weight thermoplastic material tubular in shape of a size to sustain the balloon and a payload in flight, the material being non-extensible to limit the floating altitude, a seal across one end comprising a weld across the tubular material, and a similar weld across the other end, the envelope being completely sealed and devoid of gas and adapted to being cut open for inflation with a lifting gas.

20. 11. The method of sending a balloon aloft with a load and stopping its ascent at a definite altitude which comprises inserting a payload through an opening in a non-extensible balloon envelope so that said payload will be enclosed

25. 30. within the envelope, inflating the envelope of non-extensible material with sufficient gas to lift the weight of the load and balloon and terminating the inflation before the balloon is filled leaving the balloon envelope partially collapsed, completely sealing the balloon envelope preventing the gas from escaping to atmosphere as it expands when the balloon ascends, and launching the sealed partially collapsed balloon with the balloon filling out as the gas expands as it ascends, the non-extensible material preventing further expansion of the gas and further enlarging of the balloon volume when the balloon becomes filled out thus stopping the ascent and causing the balloon and load to float at the altitude determined by the fixed maximum volume

35. 45. of the non-extensible balloon envelope.

12. 50. A load-carrying balloon comprising a balloon envelope of light weight thermoplastic material tubular in shape, the material being non-extensible to limit the floating altitude, a closure for the tubular material comprising a heat seal joining the edges completely across the tubular material, and a similar heat seal joining the edges completely across the other end of the tubular material, and a quantity of lifting gas within the balloon insufficient to completely distend the balloon at ground level and expanding with decreased air pressure as the balloon ascends.

13. 55. A load-carrying balloon comprising a balloon envelope of light weight material tubular in shape and of a size to support a payload in flight, the material being non-extensible to limit the floating altitude, a closure for the tubular envelope comprising a seal joining the edges completely across the end, and a similar seal joining the edges completely across the other end, a load sealed within the balloon protected from the elements within the sealed balloon, and a quantity of lifting gas within the balloon not sufficient to completely distend the balloon at ground level to allow room for expansion of the gas within the sealed balloon as the balloon ascends.

14. 70. The method of sending a balloon aloft and stopping its ascent at a definite altitude which comprises inflating a balloon envelope of a non-

extensible material with sufficient gas to lift the weight of the balloon and terminating the inflation before the balloon is filled, leaving the balloon envelope partially collapsed, completely sealing the balloon envelope preventing the gas from escaping to atmosphere as it expands when the balloon ascends, and launching the sealed partially collapsed balloon with the balloon filling out as the gas expands as it ascends, the non-extensible material preventing further expansion of the gas and further enlarging of the balloon volume when the balloon becomes filled out thus stopping the ascent and causing the balloon to float at the altitude determined by the fixed maximum volume of the non-extensible balloon envelope.

15. The method of sending a payload aloft with a balloon which comprises cutting an opening in a sealed uninflated non-extensible balloon envelope, inserting the payload into said opening so that it will be enclosed within the envelope, inflating the balloon through said opening with an amount of lifting gas sufficient to lift the bal-

10

20

loon and payload but not sufficient to distend the balloon at ground level, and closing said opening and completely sealing the balloon so that the expanding gas will distend the balloon as it ascends into a lower air pressure preventing the expanding gas from escaping to atmosphere.
